HENRY ALLEN HINCHCLIFF, OF COLLEGE POINT, NEW YORK

TOBACCO STRIPPING AND BOOKING MACHINE

Application filed April 24, 1930. Serial No. 446,834.

The present invention relates to machines for stripping and booking tobacco leaves and consists of improvements in construction, in arrangement and in operation offering material advantages over the machines as heretofore employed for a like purpose.

Important improved features of the present invention include: an improved cutting arrangement employing a novel type of rotary cutter designed to conform to the tapered contour of the stem to be severed so as to effect a substantial reduction of waste leaf membrane and furthermore having a groove formation to cooperate with a pressure roller for feeding of the leaf in the stripping or destemming operation; an improved means, operative automatically, for stopping the booking drum after each cutting operation and having therewith provision for adjusting of the initial or starting position of the cutter so as to adapt the operation thereof for economically destemming different sizes of leaf as the conditions require; provision for driving of the rotary cutter and the coacting roller to have uniform speed of the opposed and coacting surfaces with special provision to compensate for change in the contact diameter of the roller thereby to reduce the wear on the cutter to the minimum; means for adjusting the pressure between the grooved roller and the cutter and special provision for supporting the leaf until deposited on the drum by the belts.

The foregoing and other important features and advantages of the present invention will be more fully understood by reference to the accompanying drawings wherein an approved embodiment of the invention is disclosed and wherein like reference characters are applied to the corresponding parts in the several views.

In the drawings:

Fig. 1 is a side elevation of the machine embodying the features of my invention taken from the left.

Fig. 2 is a view thereof in front elevation with the gear box shown in section on the line *a—a* of Fig. 3.

Fig. 3 is a right hand elevation of the ma-

chine with gear box shown in section on the line *b—b* of Fig. 2.

Fig. 4 is a vertical sectional view of the drum, cutter and upper roller, with the front shown down, taken on line *c—c* of Fig. 2, with a portion of the knife or cutter broken away.

Fig. 5 is a partial sectional view taken on line *d—d* of Fig. 1.

Fig. 6 is a section, taken in a near horizontal plane, of the upper roller on line *e—e* of Fig. 1.

Fig. 7 is a central vertical cross section of the drums and cutter taken on line *f—f* of Fig. 4.

Fig. 8 is a diagrammatic view showing the development of the knife or cutter.

Fig. 9 is a detail sectional view of the clutch release pin taken on line *g—g* of Fig. 3.

Fig. 10 is a vertical sectional view of the clutch taken on line *h—h* of Fig. 3 and

Figs. 11 to 13 are detail sectional views of the cutter and coacting pressure roller taken on lines *x—x*, *y—y* and *z—z* of Fig. 8 respectively.

In the approved embodiment of the features of my present invention as here shown, the supporting parts include the left side frame 1 connected to the right side frame member 2 by a rear cross frame member 3, the front cross frame 4 and the foot treadle bearing and tie rod 5. On the frame 2 is supported the motor bracket 6 supporting motor 8 energized by a suitable electric circuit and control switch not shown.

In the arrangement conventional to this type of machine, there is suitably journaled upon the frame a cylindrical carrier or booking drum 87—89 provided at its central portion with an annular knife or cutter 91 rotatable with the drum and which in the present machine is of novel form to cooperate in the cutting operation with a pressure roller 77 which is rotated whereby the coacting surfaces will move in the same direction and with a uniform rate of movement as herein-after described.

Driving connections.—Projecting from the motor 8 is the motor shaft 9 having mounted thereon the female member of a cone clutch

10. The motor shaft 9 is arranged in axial alignment with a worm shaft 11 and slidably mounted on the worm shaft 11 is the cone 14 engaged by the spring 15 interposed between it and the collar 16 fixed on the shaft. The spring normally moves the cone 14 into clutching engagement with the cup member of the clutch 10 except when disengaged as hereinafter described. With the clutch 10 engaged, the motor drives the worm shaft 11 upon which the cone clutch member is slidably keyed in the usual manner. The worm shaft has suitable bearings in the gear box 13 and is formed with a worm thread 11' meshing with the helical idler gear 19 and the helical drum gear 20.

Drum connections.—In accordance with the present invention the drum is rotated by means of the drum gear 20 with provision, 20 operative automatically, to stop the rotation at an initial or starting point determined by an adjustable and releasable stop thereby to adjust the starting point with relation to the portion of the cutter suited for destemming leaves of a given size. In accordance therewith, the drum gear 20 has affixed thereto by rivets a ratchet wheel 22 and is pinned to the drum shaft 23. The latter shaft has freely journalled thereon the stop arm 25, the position of which is controlled by the hand wheel 26 having a tongue 26' fitted within a groove in the stop arm as shown. The hand wheel 26 is mounted freely upon the drum shaft 23 and is maintained in position thereon by a collar 27 affixed to the shaft. The stop arm carries a stud 29 upon which is pivotally mounted the pawl 30 held in engagement with the ratchet wheel 22 by the spring 31 connected to pin 32 on the pawl and to pin 32' 30 on the stop arm. By moving the handwheel 26 clockwise (Fig. 3) the position of the stop arm 25 can be set to any desired notch, which will change the location of the stopping position with respect to the drum shaft 23 and 45 with respect to any of the parts connected thereto. As the drum shaft 23 is caused to rotate only in a clockwise direction by the worm 11' a coacting stop is provided and positioned to be engaged by the stop arm and 50 which shall be releasable at the will of the operator for restarting after the stop engagement has operated. In the stopping action it is arranged whereby the coacting stop is mounted to be movable upon engagement therewith of the stop with provision for transmitting the movement to the clutch member for disengaging the same. This provision as 55 shown includes a forked clutch operating arm 33 having projections 33' fitted within a groove 14' formed in the clutch cone member. The operating arm 33 is suitably fastened to a shaft 34 journalled in bearings in the frame members 1 and 2. The releasable 60 stop as shown comprises a stop pin 40 slidably fitted in coacting stop arm 41 and main-

tained in its outer position by the action of spring 42 (Fig. 9). As shown in Fig. 3, the stop pin 40 is normally positioned to be engaged by the stop arm 25 and can be moved or retracted from its engaging position by means of a slotted arm 43 engaging a cross pin 44 on the stop pin and slidably in slot 41' of the arm 41 and projecting into the slot of arm 43. The arm 41 is pivotally mounted upon a stud 45 carried by the frame 2 and is maintained in its upper position for engagement by the stop arm 25 by the spring 46. The arm 41 is formed with a projection 41' as shown positioned to engage the end of the clutch operating arm 33 whereby upon engagement of the stop arm 25 with the coacting pin 40, movement will be imparted to the latter and transmitted by the engagement of the projection 41' with the clutch operating lever to the clutch cone member so as to disengage the clutch for stopping of the drum rotation.

The slotted arm 43 is fastened to shaft 47, the latter being journalled in the frame 2 and carrying, inside the frame, the arm 48 likewise rigidly fastened to the shaft. The arm 48 is connected to be operated by the foot treadle 51 by means of the link 49 pivotally connected by stud 50 to the arm and by stud 52 to the treadle; the treadle being mounted upon the bearing rod 5. A spring 53 is, as shown, arranged by its connection to the link 49 to operate normally to elevate the treadle and in consequence maintain the stop pin 40 in position for engagement by the stop arm 25. The treadle 51, which is the right hand foot treadle, accordingly controls the single or one revolution action of the machine and when it is desired to start the machine this treadle is depressed and instantly released. This effects the retraction of the stop pin 40, allowing spring 46 to move arm 41 upwardly to release clutch operating arm 33 which then permits spring 15 to move the cone member 14 in frictional clutch engagement. Releasing the foot treadle allows the pin 40 to again assume its position for engagement by the stop arm 25 to again stop the machine upon the completion of the single revolution of the drum.

Instant stop.—A second foot treadle control, left hand side as here shown, is provided with suitable connections to the clutch for disengaging the clutch to stop the machine at the will of the operator and at any interval of the drum revolution. For this purpose, inside of the left hand frame 1, there is fastened on the shaft 34, an arm 35 which is operated by a link 36 connected to studs 37 and 39 from the foot treadle 38 mounted on the bearing rod 5 convenient to the left foot of the operator.

Cutter roll drive.—As shown in Fig. 6, the helical idler gear 19 has formed therewith the knife roller drive sprocket 59 and the brush

drive sprocket 60. This gear runs freely on the shaft 56 and is maintained in alignment on said shaft by the side frame 2 and the collar 57 affixed to the shaft. The shaft 56 is journalled to turn freely in the frame members 1 and 2. A knife roller supporting arm 61 and coating arm 63 and a pressure adjustment arm 65 are affixed to the shaft 56 which also carries a knife roller scraper 67 secured by stud 68 which is positioned to allow the scraper to swing laterally to maintain proper engagement with the roller 77. The arms 61 and 63 have bearings at their outer ends for the knife roller shaft 69 which is positively driven by the chain 72 running over sprocket 70 keyed upon the roller shaft. The shaft 69 passes through an opening in the bracket 73 which acts as a closure member for the gear box 13. This opening is enlarged to allow the shaft 69 to swing up and down as the drum or cutter radius varies as hereinafter described.

The belt rolls 74 and 75 are journalled freely on the shaft 69 and positioned centrally between these rollers is the cutter roller 77 keyed on the shaft to be positively driven therewith. The key 76 therefor is slightly elongated allowing lateral shifting of the cutter roller to maintain proper bearing upon the rotary cutter, which supports the roller assembly and which may not always run true. This lateral movement accordingly will allow the roller to bear equally on the spaced cutting edges of the cutter or drum knife. The roller 77 has a groove as shown adapted to receive the upper portion of the stem as hereinafter described. The pressure control arm 65 has a weight 79 adjustably mounted thereon for adjusting the pressure of the roller upon the knife or cutter. The pressure, as will be understood is supplemented by the weight of the parts mounted on arms 61 and 63 and by the pull of the usual booking belts 79, 80, 81, 82, 83 and 84.

Drum and cutter.—As shown in Fig. 7, the drum shaft 23 has its bearings in frame members 1 and 2 and is located laterally by the hub of drum gear 20 and a fixed collar 85. The drum member 87 is fastened to the shaft 23 by the pin 88 and the complementary drum member 89 is fastened to said shaft by the pin 90. The annular cutter or knife 91 is as shown fitted to inwardly extending flanges formed on the respective drum members 87 and 89 and is rotatively secured thereon by the pin 92 extended through an aperture in the cutter and fitting registering holes in the drum members.

The cutter 91, in accordance with an important feature of the present invention, is formed as best shown in Figs. 2, 4, 7 and 11 with a central peripheral groove bounded at the outer sides by the opposite cutting or knife edges 91'. The knife edges, as best shown in the development thereof in Fig. 8,

are arranged with the cutting portions thereof in angular relation progressively diminishing in spaced relation or cutting width from a point *a* to the point *b* so as to conjointly form a cutter adapted to sever the stem from the leaf membrane with a tapering cut. The cutting portion of the knife from *a* to *b* has a tapering relation conforming to the taper of the average stem of the leaf to be stripped. The compromise portion of the cutter from *b* to *c* having reverse angularity of the edges is adapted to act as a clamp or gripper for heavy stems.

The groove formed in the knife or cutter between the cutting edges 91' thereof is made to conform substantially to shape of the lower portion or half of the leaf stem, with a slight reduction in size so as to effect a compression of the stem in coaction with the cutter roller 77 thereby to effect a gripping of the stem to draw the leaf in until the belts obtain a securing grip upon the membrane. At the outer side of the cutting edges, the cutter is beveled as best shown in Fig. 11, providing inclined shoulders for supporting the inner edge of the leaf membrane until deposited upon the drums by the belts 81 and 82.

The cutting action of the machine as described is as follows: the operator feeds the tip of the stem into the grooves of the upper roller and the drum knife or cutter wherein the stem is compressed so that the leaf is pulled into the machine. The stem fits into the grooves so that the upper half portion is in the roller groove and the lower half portion thereof is in the cutter groove, positioning the membrane of the leaf at the level of the cutting edges. As these are shaped to correspond to the shape of the stem, the resulting cut will be close to the stem and leave very little of the valuable leaf membrane on the stem. The groove between the cutting edges of the cutter is further formed to decrease in depth as the distance between the edges becomes less, thereby providing for a constant pull on the stem and permitting easy feeding of the leaf to be stripped. As previously explained, the pressure between the roller and the cutter may be adjusted by the movement of the weight 79 on the arm 65 to obtain an effective cutting pressure.

As described, the width of the cutting edges or spaced relation varies from a maximum as shown at *a* to the minimum width at *b*. Due to the fact that the roller 77 is supported by the cutting edges of the cutter and that the groove in the roller 77 is concaved in cross sectional contour, as the width of the cutting edges decreases they will come in contact with a smaller radius or diameter of the roller. As both the roller and cutter are positively driven this variation of contact diameter tends to alter the relative speeds of the coating or contact surfaces. To com-

pensate for this condition and to the end of maintaining substantially uniform surface speed of the coating surfaces, the radius of the cutting edges is arranged as shown best in Fig. 4 to progressively lessen or decrease in diameter from the initial or starting point *a* to a degree required for maintaining constant relative surface speed of the coating surfaces of the cutter and roller.

- 10 When the stripped stem emerges from the grooves between the cutter 91 and the roller 77 the stem may do any one of three things. It may cling to the knife roller 77 from which it will be removed by the scraper 67
 15 to drop onto the belts which will deposit it into a chute 130. It may drop directly onto the belts which will convey it to the chute or it may adhere to the knife to be removed by a scraper 131 provided on the rear cross frame 3 which likewise supports the chute. A chute cover 132 is provided to prevent the stems from getting entangled in the belts, the cover being supported between the side frames 1 and 2.

- 20 *Brush connections.*—As best shown in Figs. 2 and 6, the idler gear 19 also has formed with it the sprocket 60 which drives through chain 93 the brush sprocket 94 secured on a brush shaft 95. This brush shaft, 25 as best shown in Fig. 5, is journaled in frame member 2 and has at its inner end a recess adapted to receive a key projection of a brush 96. The other end of the brush fits in a recess 97 of a sleeve 97 journaled on a stud 98 driven into the frame 1. The brush 96 is arranged so that when the pivotal front 99 is up it will be in position to remove the tips of the leaves from the belts 81 and 82 and throw them back upon the drum where 30 they belong. The swinging front 99 is pivotally supported upon the shaft 104, the end portions of which are eccentric with respect to the portion of the shaft on which the front 99 is mounted. The left hand eccentric 104' 35 projects beyond frame 1 and has a handle 105 by which the shaft 104 may be rotated in its eccentric bearings and cause the front to be raised or lowered. The belts 79, 80, 81, 82, 83 and 84 pass over the front return rollers 50 100 and 101 which run freely on shafts 102 and 103. Shaft 102 projects beyond the left side frame 1 so that the operator can use it for a handle to swing the front out against a stop pin 107 when it is desired to remove 55 the stripped and booked leaves from the machine. The front rollers are prevented from resting against the drum by the front projection 99' bearing against a pin 106 on the frame.
 60 *Belts.*—As best shown in Figs. 1 and 2, the endless belts 79, 80, 81, 82, 83 and 84 pass from the upper return rollers 74 and 75 around the drums 87 and 89 by which they are driven by frictional engagement and during the operation 65 by engagement with the leaves inter-

posed between the belts and the drum. Upon leaving the drum the belts pass over the front return rollers 100—101 (Figs. 4 and 5), under the idler roller 108, which rotates freely on shaft 109, over idler roller 110 on shaft 111, under tension rollers 112, 113, 114, 115, 116 and 117 (Fig. 2), over upper return guide roller 118 journaled on a shaft 119 and thence back to the upper return rollers 74—75. The tension rollers 112 to 117 have individual pivoted and weighted mountings each of which consists of studs 120 upon which the rollers are journaled, the studs 120 being mounted on tension arms 121. The tension arms are all mounted upon a shaft 127 on which they swing freely. Each arm is provided with a slideable weight 129 adjustable in position for adjusting the tension of the associated belt.

Operation.—Before starting to strip any tobacco the drum knife or cutter should be set to that position at which the cutter groove will compress the stem and leave a minimum of membrane on the stripped stem. If the power is on, the operator depresses both treadles thereby disengaging the clutch and withdrawing the release pin 40 from engagement with the stop arm 25. The handwheel 26 can now be rotated clockwise (from right hand side) to the desired position. This position will be where the width of the knife is slightly less than the width of the stem and somewhere between the points *a* and *b* (Fig. 7). Care will be taken to have the cutting completed before the end of the leaf reaches point *b*. Frequently in stripping fine wrapper where a very fine cut is desirable the rear end of the leaf will be set so as to just reach the point *b*. After the setting is accomplished the treadles will be released and the drum 87—89 will rotate until the stop arm 25 engages the coating pin 40, thereby stopping the machine. Thereafter the machine will always stop at this set point except when the operator neglects to release the right hand foot treadle or unless the machine is temporarily stopped by the depression of the left foot treadle 38.

The operator now sits in front of the machine and takes one of the leaves to be stripped and feeds the butt or larger end of the stem into the grooves between the roller 77 and the cutter 91. Both foot treadles are depressed, the right one momentarily. The release of the left foot treadle 38 allows the machine to run and the stem is gripped by compression within the grooves. The entire leaf is opened by the hands permitting the leaf to slip through the fingers. From time to time, as the leaf is drawn into the machine faster than it can be properly opened, the motion is retarded or stopped by the operator by depressing the left foot treadle 38. When the leaf has been completely drawn into the machine the operator releases the left foot

5 treadle permitting the machine to pass through the remainder of its cycle at its fastest speed. During this time the operator is picking up another leaf to begin the cycle over again as soon as the machine has stopped.

As the leaf is drawn into the machine by the compression of the stem, the knife edges sever the leaf on either side of the stem. The 10 stem, passing through the grooves, is disposed of as previously described. The half of each leaf is deposited on the drum members by the belts and is carried around on the drum members until the machine is stopped 15 as described. As the machine will be again started at the same point on the drum and the leaf will be fed at the same time, it will be laid on top of the previous leaf. This operation will be repeated until a "book" is 20 formed. When the required number of leaves to complete the book have been fed into the machine they are removed in a group. This is done by allowing the machine to the stop position. Both treadles are now depressed 25 and held down. The front 99 is pulled from the in position against pin 106 (shown in Fig. 1) to the outer or open position against pin 107 (shown in Fig. 4), by pulling on the extension of shaft 102. The ends of each 30 book will be (if properly fed) under the front and in such position that they can be taken, one in each hand. The pressure on the left treadle 38 is now released slightly so that the drum advances a little and by doing 35 this alternately the stripped leaves may be drawn from the machine in perfect condition. Upon closing of the front a new lot may then be started.

While I have described and shown an 40 approved embodiment of the features of the present invention, it will be understood that the disclosure is illustrative and that varied modifications thereof may be made without departing from the scope of the invention as 45 defined in the appended claims. As an example thereof, while I have shown my improved cutting arrangement comprising a cutter having its cutting edges in tapered relation to correspond to the taper of the stem 50 and cooperating with a pressure roller each of which is positively driven, it will be understood that if desired the roller may be mounted as an idler and frictionally driven and in this case the cutter may be formed with the 55 tapered cutting edges and groove therebetween to possess the important advantages as described but of a concentric form as the necessity of compensating for variation of the contact diameter with the roller would 60 then be eliminated.

Having described my invention, I claim:

1. A tobacco stripping machine comprising a rotary drum, a cutter carried by the drum and provided with opposite cutting 65 edges in angular relation adapted to produce

a cut tapered substantially to conform to the taper of the leaf stem, means operative automatically to stop the drum at a determined starting position and means for adjusting the operative relation of the cutter and starting position for adjusting the cutter action 70 to different sizes of leaves.

2. A tobacco stripping machine comprising a rotary drum, a circular cutter carried by the drum and provided with opposite cutting edges in angular relation adapted to produce a cut tapered substantially to conform to the taper of the leaf stem, means for rotating the drum, means operative automatically to stop the drum at a predetermined starting position, said latter means being adjustable to establish an initially effective portion of the cutter edges suited to the larger end of the leaf stem to be severed. 75

3. A tobacco stripping machine comprising a rotary drum, a circular cutter carried by the drum and provided with opposite cutting edges in angular relation adapted to produce a cut tapered substantially to conform to the taper of the leaf stem, a pressure roller suitably journalled to bear upon the cutting edges to coact therewith in the cutting operation, means operative automatically to stop the drum at a starting position 80 and means for adjusting the operative relation of the cutter and starting position for adjusting the cutter action to different sizes of leaves. 85

4. A tobacco stripping machine comprising a rotary drum, a circular cutter carried by the drum and provided with opposite cutting edges in angular relation adapted to produce a cut tapered substantially to conform to the taper of the leaf stem, a pressure roller suitably journalled to bear upon the cutting edges to coact therewith in the cutting operation and provided with a groove circumferentially thereof to receive the stem, means for rotating the cutter and roller to have uniform coacting surface speed, means operative automatically to stop the drum at a predetermined starting position and means for adjusting the operative relation of the cutter and starting position for adjusting the cutter action to different sizes of leaves. 100 105

5. A tobacco stripping machine comprising a rotary drum, a circular cutter carried by the drum and provided with opposite cutting edges in angular relation adapted to produce a cut tapered substantially to conform to the taper of the leaf stem, a pressure roller suitably journalled to bear upon the cutting edges to coact therewith in the cutting operation, said cutter being formed with a groove between the cutting edges having a progressive reduction in size to have feeding engagement with the stem, means for rotating the drum and means operative automatically 110 115 120 125 130 135 140 145 cally to stop the drum at a predetermined starting position.

6. A tobacco stripping machine comprising a rotary drum, a circular cutter carried by the drum and provided with opposite cutting edges in angular relation adapted to produce a cut tapered substantially to conform to the taper of the leaf stem, a pressure roller suitably journaled to bear upon the cutting edges to coact therewith in the cutting operation, said cutter and roller being formed with grooves for feeding engagement with the stem, means for rotating the cutter and roller to have uniform coacting surface speed, adjustable means for applying pressure of the roller on the cutter, means for rotating the drum and means operative automatically to stop the drum at a predetermined starting position.

7. A tobacco stripping machine comprising a rotary drum, a circular cutter carried by the drum and provided with opposite cutting edges in angular relation adapted to produce a cut tapered substantially to conform to the taper of the leaf stem, a roller pivotally supported to bear upon the cutter to coact therewith in the cutting operation, adjustable means for applying pressure on the roller, said cutter and roller being relatively formed for gripping the leaf stem under compression for feeding the leaf, means for rotating the drum and means operative automatically for stopping the drum at a predetermined starting position.

8. A tobacco stripping machine comprising a rotary drum, a circular cutter carried by the drum and provided with opposite cutting edges in angular relation adapted to produce a cut tapered substantially to conform to the taper of the leaf stem, a roller pivotally supported to bear upon the cutter to coact therewith in the cutting operation, adjustable means for applying pressure of the roller on the cutter, said cutter and roller being relatively formed for gripping the leaf stem under compression for feeding of the leaf during the cutting operation, means for rotating the drum and roller to have substantially uniform speed of their coacting surfaces and means operative automatically for stopping the drum at a predetermined starting position.

9. A tobacco stripping machine comprising a rotary drum, a circular cutter carried by the drum and provided with opposite cutting edges in angular relation adapted to produce a tapered cut substantially conforming to the taper of a leaf stem, a roller pivotally supported to bear upon the cutter to coact therewith in the cutting operation, said cutter being formed with a circumferential groove intermediate of the cutting edges of progressively diminishing depth as the cutting edges decrease in spaced relation and having annular shoulders at the outer sides

of the cutting edges for supporting the leaf, means for rotating the drum and means operative automatically for stopping the drum at a predetermined starting position.

10. A tobacco stripping machine comprising a rotary drum, a circular cutter carried by the drum and provided with opposite cutting edges in angular relation adapted to produce a tapered cut substantially conforming to the taper of the leaf stem, a roller pivotally supported to bear upon the cutter to coact therewith in the cutting operation, said roller being formed with a circumferential groove to receive the upper portion of the leaf stem, means for rotating the drum and the roller to effect substantially uniform movement of the coacting surfaces of the roller and cutting edges and said cutting edges being formed of progressively reduced diameter as their spaced relation decreases to compensate for reduction in diameter of the engaged portion of the roller, means for rotating the drum and means operative automatically for stopping the drum at a predetermined position.

11. A tobacco stripping machine comprising a rotary drum, a circular cutter carried by the drum and provided with opposite cutting edges in angular relation adapted to produce a cut tapered substantially to conform to the taper of a leaf stem, means for rotating the drum and means operative automatically for stopping the drum at a predetermined starting position, said latter means comprising a stop arm rotatively secured to the drum and adjustable angularly with relation thereto and a coacting stop positioned to be engaged by the stop arm, said coacting stop being shiftable from engaging position for restarting.

12. A tobacco stripping machine comprising a rotary drum, a circular cutter carried by the drum and provided with opposite cutting edges in angular relation adapted to produce a cut tapered to conform to the taper of the leaf stem, means for rotating the drum including a shiftable clutch member and means operative automatically for stopping the drum at a predetermined starting position consisting of a stop arm rotatively secured to the drum and adjustable angularly with relation thereto, a coacting stop positioned to be engaged by the stop arm, connections from the latter stop to the clutch member, said coacting stop being shiftable from engaging position and treadle connections thereto for shifting of said stop for starting of the machine.

13. A tobacco stripping machine comprising a rotary drum, a circular cutter carried by the drum and provided with opposite cutting edges in angular relation adapted to produce a cut tapered to conform to the taper of the leaf stem, means for rotating the drum including a shiftable clutch member and

means operative automatically for stopping the drum at a predetermined starting position consisting of a stop arm rotatively secured to the drum and adjustable angularly with relation thereto, a coacting stop positioned to be engaged by the stop arm and connected to transmit movement to the clutch member, said coacting stop being provided with a contact pin slidably mounted therein, means operative normally to move said pin into engaging position, treadle connections to said pin for retracting same for starting of the machine and a second treadle with connections to the clutch member for manually stopping of the machine at the will of the operator.

14. A tobacco stripping machine comprising a rotary drum, a circular cutter carried by the drum and provided with opposite cutting edges in angular relation adapted to produce a cut tapered substantially to conform to the taper of the leaf stem, a pressure roller suitably journaled to bear upon the cutting edges to coact therewith in the cutting operation, said roller being formed with a circumferential groove and being mounted to have lateral shifting movement for maintaining proper engagement with the cutting edges, means for rotating the drum and means operative automatically for stopping the drum at a predetermined starting position.

15. A tobacco stripping machine comprising drum composed of aligned cylindrical drum sections suitably journaled, a circular cutter supported upon inner flanges of the drum sections, said cutter being provided with opposite cutting edges in angular relation adapted to produce a cut tapered substantially to conform to the taper of the leaf stem, said cutter being formed with a central groove between the cutting edges adapted to receive the stem, a roller pivotally supported to bear upon the cutter and formed with a central circumferential groove to coact with the cutter groove for pressure feeding engagement with the stem, said roller being supported to have lateral movement to insure proper engagement with the cutter, means for rotating the drum, means operative automatically to stop the drum at a predetermined starting position, said latter means being adjustable to establish an initially effective portion of the cutter suited to the larger end of the leaf stem to be severed and manually operated means for interrupting the rotation of the drum at the will of the operator.

16. A tobacco stripping machine comprising a rotary drum, a circular cutter carried by the drum and provided with opposite cutting edges in angular relation adapted to produce a cut tapered substantially to conform to the taper of the leaf stem, a pressure roller suitably journaled to bear upon the

cutting edges to coact therewith in the cutting operation, said cutter being formed with a groove between the cutting edges for feeding engagement with the stem and means for rotating the drum.

17. A tobacco stripping machine comprising a rotary drum, a circular cutter carried by the drum and provided with opposite cutting edges in angular relation adapted to produce a cut tapered substantially to conform to the taper of the leaf stem, a pressure roller suitably journaled to bear upon the cutting edges to coact therewith in the cutting operation, said cutter and roller being formed with grooves for feeding engagement with the stem, adjustable means for applying pressure of the roller on the cutter and roller to have uniform coacting surface speed.

18. A tobacco stripping machine comprising a rotary drum, a circular cutter carried by the drum and provided with opposite cutting edges in angular relation adapted to produce a cut tapered substantially to conform to the taper of the leaf stem, a roller pivotally supported to bear upon the cutter, adjustable means for applying pressure of the roller on the cutter, said cutter and roller being relatively formed for gripping of the leaf stem under compression for feeding the leaf and means for rotating the drum.

19. A tobacco stripping and booking machine comprising a rotary drum, a cutter carried by the drum centrally thereof, means for rotating the drum, belt supporting rollers arranged to support booking belts at opposite sides of the cutter and to pass from an upper frontal reversing position rearwardly to a lower frontal reversing position and including a roller pivotally supported at the latter position, a pivotally supported swinging front for supporting the latter roller, a brush suitably journaled and positioned to deflect the leaves onto the drum from the belts as the latter pass over the lower reversing roller and the pivotal support of the swinging front being adjustable for raising and lowering the lower reversing roller with relation to the brush, substantially as described.

Signed at College Point, in the county of Queens and State of New York, this 14 day of April, A. D. 1930.

HENRY ALLEN HINCHCLIFF.
